SLIDE FASTENER STRINGER TAPE
REINFORCEMENTNoel J. Poux, Meadville, Pa., assignor to Talon,
Inc., a corporation of Pennsylvania

Application March 9, 1940, Serial No. 323,183

3 Claims. (Cl. 112—262)

This invention relates to the manufacture of slide fasteners and, in particular, to the reinforcement of textile or other stringer tapes at the edges to which slide fastener interlocking elements are to be clamped or otherwise secured.

It is an object of this invention to provide a method of attachment of tape edge reinforcing cords, wherein the cords are attached most firmly to the stringer tape edges.

It is a further object of this invention to provide a method wherein the attachment to the stringer tape edges of oppositely wound edge reinforcement cords is accomplished with relief of internal torsional stresses in the attached tape edge reinforcement cords.

It is a further object of this invention to provide such a method wherein the tape is exactly concentrically disposed with respect to the cords at opposite sides or, in other words, wherein the cords are of equal size because of equal compression thereof.

It is a further object of this invention to eliminate "peeling" of the cords from the tape after the attachment of slide fastener interlocking elements to the reinforced tape edges because of the elimination of torsional stresses in the reinforcing cords prior to attachment of the slide fastener interlocking members.

It is a further object of this invention to provide for increase in the compression in the cord reinforced edge of the stringer tape and to secure uniformity and consequent decrease in the fixed tape radius which advantageous features are incidents of the compression, to the same degree, of both cords applied to the tape.

These and other objects and advantages of the invention will appear from the following description taken in conjunction with the accompanying drawings which form a part thereof, and will be pointed out in the appended claims.

In the drawings:

Fig. 1 is a view in perspective, and partly in section, illustrating the initial sewing step of this invention;

Fig. 2 is a transverse section taken substantially on the line 2—2 of Fig. 1;

Fig. 3 is a longitudinal section taken substantially on the line 3—3 of Fig. 2;

Fig. 4 is a view similar to Fig. 2, but showing a known form of slide fastener interlocking member attached to a cord reinforced stringer tape wherein the attachment is achieved by a single sewing step, as shown in Figs. 1, 2 and 3;

Fig. 5 is a view similar to Fig. 1, but illustrat-

ing the second or added sewing step of this invention;

Fig. 6 is a transverse section taken substantially on the line 6—6 of Fig. 5;

Fig. 7 is a plan view of a double-sewed cord reinforced as illustrated in Fig. 1, with interlocking fastener members attached thereto;

Fig. 8 is a transverse section similar to Fig. 4, taken substantially on the line 8—8 of Fig. 7, and illustrating the elimination of "peeling" by the double sewing of the cord according to this invention;

Fig. 9 is a plan view of double stitched cord reinforced stringer tape, wherein the stitching is superposed or substantially in line;

Fig. 10 is a longitudinal section taken substantially on the line 10—10 of Fig. 9;

Fig. 11 is a view similar to Fig. 9, but showing staggered double stitching; and

Fig. 12 is a transverse section taken substantially on the line 12—12 of Fig. 11.

In former methods of reinforcing the slide fastener interlocking member supporting edge of stringer tapes by the attachment, at opposite sides thereof, of oppositely wound reinforcing cords, a single line of stitching extending through the cords and the intervening tape edge has been used for attaching the cords to the tape edge, see Fig. 1.

In such methods the upper reinforcement cord is compressed to a greater degree than the lower reinforcement cord due, no doubt, to the fact that the needle stresses the upper thread to a higher degree than does the bobbin stress the lower thread.

In many cases, this causes the interlock of the upper and lower threads to deviate from the exact central axis of the intervening tape. Likewise, the line of stitching is, quite often, spaced from the longitudinal axis of the cords. This, in addition to the action of the needle, reciprocating feed dog and stationary throat plate of the machine, causes internal torsional stresses to be applied to the respective cords which are wound in opposite directions or, in other words, clockwise and counterclockwise, as seen in Fig. 2.

When a slide fastener interlocking member is clamped or otherwise applied to the attached reinforcement cords, these cords which are under internal torsional stresses, will tend to unwind upon dissipation of temporary torsional stresses in such manner that the interlocking fastener is thrust outwardly from the reinforced edge, as shown in Fig. 4. This substantially impairs the firm attachment of the interlocking fastener

member upon the reinforcement tape edge, and is known as "peeling." The interlocking fastener member, as shown in Fig. 4, is not concentric with respect to the tape due to the greater compression and consequent lesser size of the upper tape edge reinforcement cord, as compared with the lower tape edge reinforcement cord. These highly disadvantageous features of cord reinforced stringer tapes produced by prior known methods are totally obviated, according to the principles of this invention.

According to the principles of this invention, by securing equal compression of the upper and lower tape edge reinforcement cords, the stringer tape is maintained exactly concentric with respect to the reinforced edge thereof. The tendency toward peeling is eliminated by double stitching because of the equalization of the inequalities in thread tensions at opposite sides of the reinforced tape edge. Likewise, the compression of the reinforced tape edge is increased whereby the difference in length between the reinforced tape edge and the unreinforced tape edge is emphasized or, in other words, the fixed radius of the stringer tape is reduced. As the flexibility of the stringer tape in the finished fastener varies inversely with the "fixed radius" of the tape, any decrease in the "fixed radius" of the stringer tape is accompanied by increased flexibility of the stringer tapes and consequent improvement in the easy running properties of the fastener.

Referring to the drawings in detail and with reference particularly to Figures 1 to 4, this invention may be carried out with conventional sewing apparatus such as the machine shown in Fig. 1, having an operating head 14 with reciprocating needle 15, and provided with a presser foot 16 having a reinforcement cord accommodating channel 17 for accommodating that tape edge reinforcement cord which is uppermost in the first sewing step. The machine is provided with a movable feed dog 18 which is surrounded by a stationary throat plate 19 having a suitable trough-like channel 20 for accommodating that tape edge reinforcement cord, which is lowermost in the first sewing step. The tape is designated 21, the tape edge reinforcement cord, which is uppermost in the first sewing step, is designated 22, and the tape edge reinforcement cord, which is lowermost in the first sewing step, is designated 23.

The needle 15 carries a thread 24 and the bobbin carries the thread 25. These threads are interlocked in a lock stitch, as shown in Figs. 2 and 3. The needle thread 24 will be hereinafter referred to as the first needle thread and the bobbin thread 25 will be hereinafter referred to as the first bobbin thread for reasons which will hereinafter most clearly appear. When most ideal conditions exist, the interlock of the threads 24 and 25 will occur centrally of the plane of the tape 21, as shown in Figs. 2 and 3. The threads 24 and 25, however, will rarely pass directly through the centers or longitudinal axes of the reinforcing cords 22 and 23, but will generally pass to one side thereof, as shown in Figs. 2 and 4.

As shown in Fig. 4, when the legs of the slide fastener interlocking member 26 are clamped upon the attached tape edge reinforcing cords shown in Fig. 2, the cords, which are oppositely wound, as described above, will tend to seek a state of equilibrium wherein the applied internal torsional stresses are dissipated. This dissi-

pation of the internal stresses in the cords will tend to cause them to unwind in such manner as to thrust the slide fastener interlocking member 26 outwardly of the tape 21, as clearly shown in Fig. 4. As above described, this is known as "peeling" and materially impairs the secure attachment of the slide fastener interlocking members on the tape 21. As former methods of reinforcing cord attachment terminated with the above described single sewing step, the defects incident to "peeling" were prevalent in fasteners manufactured from tapes so reinforced.

According to this invention, the above-described initial step constitutes merely a part of the stringer tape reinforcing method, instead of the entire method. According to the method of this invention, the continuous stringer tape 21 with edge reinforcement cords 22 and 23 attached by the single first line of stitching (comprising the first needle thread 24 and the first bobbin thread 25) as shown in Fig. 2, is subjected to a second or reverse stitching step. This second or reversed stitching step is illustrated in Fig. 5.

As shown in Fig. 5, the stringer tape 21 and attached cords 22 and 23, with the first line of stitching 24, 25, is again run between the presser foot 16 and the feed dog 18 and throat plate 19. The cord 22 (which was uppermost in the first stitching step) is now the lowermost cord and is guided in the channel 20, as shown in Fig. 5. The cord 23, which was formerly the lowermost cord (now inverted) is attached by the first line of stitching to the stringer tape 21 and the channel 17 of the presser foot 16 is, therefore, inoperative in the second stitching step. The needle 15 carries the second needle thread 28 and the bobbin carries the second bobbin thread 29. In the second stitching step, the second line of stitching 28, 29 is formed by the second needle thread 28 and the second bobbin thread 29 and, necessarily, the inequalities in tension between the needle thread and bobbin thread are reversed in the second line of stitching 28, 29, as compared with the first line of stitching 24, 25. The inequalities in compression between the cords 22 and 23 are, therefore, equalized and the cord thickness is uniform, as shown in Fig. 6.

As will be readily understood from the showing of Fig. 8, the stringer tape 21 is disposed concentrically with respect to the cords 22 and 23, therefore, concentrically with respect to the attached slide fastener interlocking members 26, as shown in Fig. 8. Furthermore, as will readily appear from comparison of Figs. 4 and 8, the tendency for untwisting the cords 22 and 23 to cause "peeling" is effectively prevented by the two lines of attachment provided by the stitching 23, 25 and 28, 29. "Peeling" is thus prevented.

While the showing of Figs. 5, 6 and 7 presupposes that the lines 24, 25 and 28, 29 of stitching are straight and parallel, nevertheless, under some conditions of operation, these lines of stitching may be superposed or disposed in line. This condition is illustrated in Figs. 9 and 10. From Figs. 9 and 10, it will clearly appear that the inequalities between the compression of the respective cords 22 and 23 are eliminated, as the difference in thread tension between the first and second lines of stitching will neutralize or balance one another.

In addition to the above-described conditions, the stitches 24, 25 and 28, 29 may be "zigzag," which condition is illustrated in Figs. 11 and 12. In this condition also, the inequalities in thread

tensions between the first and second lines of stitching are also neutralized or balanced and the compression of the cords 23 and 22 is equalized.

As will clearly appear from the above description, the use of two lines of stitching to secure the reinforcement cords 23 and 22 through the edge of tape 21 increases the compression of the cords 23 and 22 over the compression achieved by a single line of stitching, as illustrated in Figs. 1 to 4. The added compression of these cords likewise increases the difference in length between the free, unreinforced edge of the stringer tape 21 and the reinforced edge thereof, or, in other words, decreases the fixed radius thereof. This increase in difference in length between the tape edges or decrease of the fixed radius, increases the flexibility of the complete fastener and materially increases the smoothness with which the fastener interlocking members 21 are engaged and disengaged.

It will thus be seen that, according to this invention, the flexibility of the fastener tapes is increased, the security of attachment of the fastener interlocking members 26 to the tape is substantially increased and complete concentricity of the stringer tape 21 with respect to the cords 22 and 23 and with respect also to the attached fastener interlocking elements is secured. The security of attachment of the fastener interlocking members 26 with respect to the tape is secured, as above described, through elimination of "peeling" by attaching the cords 22 and 23 to the tape edge without production of torsional stresses therein.

From another aspect, it may be stated that the function of the first line of stitching is to impart a temporary fixed radius to the continuous tape, while the function of the second line of stitching is to increase the acuteness of this fixed radius and lock it into the tape, or render it permanent. In this manner, the fixed radius

of the tape is substantially decreased due to the fact that the impairment of the acuteness of the radius placed in the tape by the first line of stitching 24, 25 is prevented by the locking action of the second line of stitching 28, 29.

In addition to the locking action of the second line of stitching 28, 29, this line of stitching, by increasing the compression of the cords 22 and 23 and equalizing the compression of the respective cords, increases the acuteness and uniformity of the fixed radius throughout the length of the tape.

It is, of course, to be understood that the above description is merely illustrative and in nowise limiting and that I desire to comprehend within my invention all modifications included within the scope of the appended claims.

Having thus fully described my invention, what I claim as new and desire to secure by Letters Patent is:

1. In a method of reinforcing slide fastener stringer tape, attaching oppositely twisted edge reinforcement cords to opposite sides of one edge of a stringer tape by a single line of lock stitching applied from one side of the tape while imparting to the tape a fixed radius, inverting said tape, and resistitching said cords to said tape edge by a second line of lock stitching applied from the opposite side of the tape to lock the fixed radius in said tape.
2. A new article for use in the manufacture of slide fastener stringers comprising a tape, a pair of oppositely wound cords at opposite sides of one edge of said tape, and a pair of lines of stitching extending through said cords and said tape, the needle threads of each line of stitching being disposed at opposite sides of said tape.
3. In a method as defined in claim 1, said lines of lock stitching being parallel and spaced at opposite sides of the longitudinal axes of said cords.

NOEL J. POUX.
